(57) **CLAIM**

The ornamental design electrical stimulator and mounting patch assembly, as shown and described.

DESCRIPTION

FIG. 1 is a perspective view of the electrical stimulator portion shown separately for clarity of illustration of an electrical stimulator and mounting patch assembly showing my new design.

FIG. 2 is a front elevation view thereof.

FIG. 3 is a rear elevation view thereof.

FIG. 4 is a bottom plan view thereof.

FIG. 5 is a top plan view thereof.

FIG. 6 is a right side elevation view thereof.

FIG. 7 is a left side elevation view thereof.

FIG. 8 is a perspective view of the mounting patch portion of the electrical stimulator and mounting patch assembly shown separately for clarity of illustration.

FIG. 9 is a front elevation view thereof.

FIG. 10 is a rear elevation view thereof.

FIG. 11 is a bottom plan thereof.

FIG. 12 is a top plan view thereof.

FIG. 13 is a right side elevation view thereof.

FIG. 14 is a left side elevation view thereof.

FIG. 15 is a perspective view of an electrical stimulator and mounting patch assembly shown assembled.

FIG. 16 is a front elevation view thereof.

FIG. 17 is a rear elevation view thereof.

FIG. 18 is a bottom plan view thereof.

FIG. 19 is a top plan view thereof.

FIG. 20 is a right side elevation thereof; and,

FIG. 21 is a left side elevation view thereof.

The broken lines are included for the purpose of illustrating portions of the electrical stimulator and mounting patch assembly that form no part of the claimed design.
